(57) **CLAIM**

The ornamental design for a toothbrush, as shown and described.

DESCRIPTION

FIG. 1 is a front perspective view from above and one side; FIG. 2 is a front view;

FIG. 3 is a rear view;

FIG. 4 is a left side view;

FIG. 5 is a right side view;

FIG. 6 is a plan view; and,

FIG. 7 is an underneath plan view.

The broken lines showing the head and parts of the handle illustrate portions of the toothbrush that form no part of the claimed design.
